(57) **CLAIM**

An ornamental design for an in-grid power distribution sensor, as shown and described.

DESCRIPTION

FIG. 1 is a perspective view from above of an in-grid power distribution sensor in a closed position;

FIG. 2 is a perspective view from below of the in-grid power distribution sensor in the closed position;

FIG. 3 is a rear plan view thereof;

FIG. 4 is a front plan view thereof;

FIG. 5 is a left side plan view thereof;

FIG. 6 is a right side plan view thereof;

FIG. 7 is a top plan view thereof; and

FIG. 8 is a bottom plan view thereof.

FIG. 9 is another perspective view from above of an in-grid power distribution sensor in an open position; and,

FIG. 10 is another perspective view from below of the in-grid power distribution sensor in the open position.

The broken lines showing an overhead powerline in FIGS. 1, 2, 9, and 10 illustrate environmental subject matter. The broken lines showing a corporate logo in FIGS. 2, 6, and 10, a label in FIGS. 2, 3, 4, 6, 8, and 10, a charge port in FIGS. 2, 3, 6, 8, and 10, a power indicator button in FIG. 6, a wired connector in FIG. 4, zig-zag teeth in FIGS. 5 and 6, edges of retracted elements in FIG. 10, and a deployment tool in FIGS. 9 and 10 illustrate portions of the in-grid power distribution sensor. None of the broken lines shown in the drawings form any part of the claimed design.

1 Claim, 10 Drawing Sheets
